UNITED STATES PATENT OFFICE.

A. S. GRANT, OF WAUPUN, WISCONSIN.

IMPROVEMENT IN CARRIAGES.

Specification forming part of Letters Patent No. 42,760, dated May 17, 1864.

To all whom it may concern:

Be it known that I, A. S. GRANT, of Waupun, county of Dodge, State of Wisconsin, have invented a new and useful Improvement in Carriages; and I do hereby declare that the following is a full, clear, and exact description thereof, reference being had to the accompanying drawings, making part of this specification, in which—

Figure 1 is a side elevation of the body and top of a buggy having my invention applied to it. Fig. 2 is an enlarged side elevation of the seat of a buggy, showing the improved shifting rail in two positions. Fig. 3 is a plan view of Fig. 2, showing the rail secured in place. Fig. 4 is a transverse sectional view of one of the locking devices which are used to secure the arms of the rail in place.

Similar letters of reference indicate corresponding parts in the several figures.

The object of my invention and improvement in attaching shifting tops to their seats is to secure a more firm and rigid fastening, and at the same time to facilitate the removal of the top from its seat and the replacing of the same thereon.

By my invention a single person can remove a top from its seat in a few minutes and with very little labor, as the top does not leave its support until in the very act of lifting it bodily from the vehicle, whereas shifting tops hitherto constructed require at least two persons to unfasten and remove them from their seats.

To enable others skilled in the art to make and use my invention, I will describe its construction and operation.

In the accompanying drawings, A represents the seat, and a the back rail, of a buggy, which parts may be constructed in any of the well-known forms and applied to the body and running-gear in the usual manner.

b b represent three eyes of a circular form, which are suitably secured to the corners and middle of the back rail, a, as shown in Fig. 3, and project from the back of this rail a sufficient distance to receive hooks c c c, which are attached to the back bar of the shifting rail, as will be further described. On each one of the side rails I apply an oblong slotted plate, d, which, being suitably secured in place, projects outward so as to receive the gibs projecting from the side bars or arms of the shifting rail, and also dogs or wedge-pointed

hooks, which are also attached to these arms. These eyes b b b and side slotted plates, d d, are formed on the iron straps, which are used to stiffen and attach the back rail, a, to the seat A, as shown clearly in Fig. 3.

The shifting rail B is constructed with two flaring arms near its ends, the back portion being made in this case straight, thus adapting it to the straight back a of the seat-rail. The extreme ends of the back portion of the rail B are provided with screws and nuts e e, and the arms of this rail are also provided with screws and nuts for the purpose of securing the top to this rail, as shown in Fig. 1.

The hooks c c c are formed on the lower edge of the back portion of the shifting rail B in such positions as will allow them to enter the respective eyes b b b and bring the rail B in a central position on the top of the seat-rail a, as shown in Fig. 3. When in this position the gibs g g may be made to enter the slots in plates d d by springing the arms on which these gibs are formed toward each other and slipping the gibs down into the slots, after which the retraction of the arms of rail B will force these gibs or notched plates g outward and against the outer ends of the slots, thus causing the gibs to embrace the plates d, as shown in Fig. 4. When the rail B has thus been secured, the whole are locked in place by the pivoted dogs or hooks s s, which are furnished with beveled or wedge-pointed keys i i, that force the gibs outward in their slots and lock them rigidly in place. The form of the notches in the gib-fastenings is flaring, so that the wedge-keys i i secure them more firmly the harder these keys are driven in their places, and thus all rattling or jarring loose of the parts is prevented. The back C of the shifting top is secured to it by the goose-necks h h and V, standard k, shown in Fig. 2.

The hooks c c c on the back rail, B, are made nearly pointed, so that in adjusting the top in place on the seat, these hooks draw very tight in their eyes b, and thus prevent rattling at these points. These hooks are curved in such manner that it is necessary to hold the top D in an almost horizontal position before the ends of these hooks will enter their eyes, after which the top is turned up, brought to the position shown in Figs. 1 and 2, and fastened in front, as above described.

The back fastening is made in the act of adjusting the top in position to effect the front or side fastening, and in detaching or removing the top, a reverse operation occurs—viz., the keys *i i* are slipped out of their slotted plates *g g* and the gibs detached from these plates by springing the arms of the shifting rail toward each other and then swinging the top back until the hooks *c* can be lifted out of their eyes.

From this description it will be seen that I secure the top to the back part of its seat by a detachable hinge-fastening which supports the top until it is thrown back, as above described, and in a convenient position to be lifted up bodily and removed. By this construction and arrangement a single person can easily and with very little labor remove a top from its seat or apply one to its seat, the hooked fastenings serving the purpose of another person and remaining in their places until in the act of lifting the top off.

Having thus described my invention, what I claim as new, and desire to secure by Letters Patent, is—

1. Combining with a detachable carriage or

buggy top and the shifting rail *B* thereof, hooks and eyes *b c*, of such a construction as will join the top to the back rail of the seat and allow of the top or cover being turned down to a convenient position for being detached, and also of being turned up on its connections when it has been attached, substantially in the manner set forth.

2. In combination with the subject-matter of my first claim, the laterally-expanding side fastenings, arranged substantially as described.

3. The combination of the hinging hook-and-eye fastenings *b c*, applied to the back of the shifting rail *B*, with the gib and wedge fastenings *g i d*, constructed and operating in the manner described.

4. The pivoted wedge-pointed dogs *s s*, in combination with gib-fastenings *g g* and receiving-loops *d d*, the same constituting side fastenings for the arms of the shifting rail, substantially as described.

A. S. GRANT.
